THREE WHEELED VEHICLE BODY

Edward Roth, 14245 San Feliciano,
La Mirada, Calif. 90638

Filed June 8, 1973, Ser. No. 368,215

Term of patent 14 years

Int. Cl. D12—08

U.S. Cl. D12—85

FIG. 1 is a front perspective view of a three wheeled vehicle body showing my new design;
 FIG. 2 is a rear perspective view thereof;
 FIG. 3 is a side elevational view thereof;
 FIG. 4 is a top plan view thereof;
 FIG. 5 is a rear elevational view thereof; and
 FIG. 6 is a front elevational view thereof.

I claim:
 The ornamental design for a three wheeled vehicle body, as shown.
